UNITED STATES PATENT OFFICE.

CHARLES E. SKELTON, OF SYRACUSE, NEW YORK.

PUFF IRON.

Application filed June 15, 1922. Serial No. 568,410.

To all whom it may concern:

Be it known that I, CHARLES E. SKELTON, a citizen of the United States of America, and a resident of Syracuse, in the county of 5 Onondaga, in the State of New York, have invented new and useful Improvements in Puff Irons, of which the following, taken in connection with the accompanying drawings, is a full, clear, and exact description.

10 This invention relates to a puff iron for steaming the shoulders of coats and various parts of other garments to renovate and restore the nap of the same either before or after pressing, the main object being to 15 enable the operator to apply the steam to the garment by simply holding the latter in the hand and pressing it upwardly against the lower perforated side of a steam distributing chamber in said puff iron whereby 20 the upward pressure will cause the application of the steam while the withdrawal of the pressure will cause the cutting off of the steam supply to the perforated wall.

In other words, I have sought to provide 25 a puff iron with a steam-heated chamber and a steam-distributing chamber connected by a valve controlled passage in such manner that the puff iron may be moved by upward pressure against its lower side to open the valve 30 and returned by its own weight to close the valve.

Other objects and uses relating to specific parts of the device will be brought out in the following description:

35 In the drawings:

Figure 1 is a side elevation of a puff iron embodying the various features of my invention.

Figure 2 is an enlarged vertical sectional 40 view taken on line 2—2, Figure 1 except that the coils of the steam supply and return tubes are shown in elevation.

Figure 3 is an enlarged longitudinal vertical section of the same device except that the intermediate portion of the pedestal is broken away and the base is shown in elevation.

Figure 4 is a horizontal sectional view of 50 the same device taken in the plane of line 4—4, Figure 1 looking upwardly from the under side, the front portion of the puff iron being broken away.

The puff iron as —1— is mounted upon a pedestal —2— having a suitable supporting 55 base —3—, which is adapted to be secured to

the table of a garment pressing machine or other convenient support.

The pedestal —2— is hollow and substantially cylindrical for receiving therein a steam supply pipe —4— and a steam return 60 or drainage pipe —5— which may be connected to any suitable source of steam supply and have their upper ends within the pedestal secured to a bracket —6— which in turn is secured by screws —7— to the inner 65 face of the rear side of the pedestal near the upper end thereof as shown in Figure 3.

The upper end of the pedestal is provided with a forwardly projecting flange 70 —8— which forms a limiting stop or seat for supporting the front portion of the puff iron —1— in a substantially horizontal plane against undue downward movement while permitting its upward movement as will be hereinafter explained, the rear portion of the 75 upper end of the standard being elevated some distance above the horizontal plane of the flange —8— to form a valve-operating shoulder —9— also hereinafter more fully described.

The opposite sides of the upper end of 80 the pedestal are provided with raised lugs 85 —10— in front of the axis of the pedestal for receiving a pivotal shaft or pin —11— by which the puff iron is pivotally connected to the pedestal.

This puff iron is provided near its rear end with a pendent hub —12—, the rear portion of which is substantially semi-cylindrical but of greater radius than that of the pedestal —2— so as to leave an intervening clearance —13— between it and the raised portion having the shoulder —9— which it is adapted to surround, the object of the clearance —13— being to permit the puff iron —1— to rock vertically about the axis of its pivot —11—.

The front portion of the hub —12— is substantially straight transversely and vertically and has its lower edge adapted to 100 normally rest upon the upper face of the flange —8— and thereby to cooperate with said flange in holding the puff iron in substantially a normal position against undue downward movement while permitting its 105 free vertical movement about the axis of the pivot —11—.

The puff iron —1— extends forwardly 110 some distance beyond the hub —12— and is preferably hollow to form a steam heated

chamber —14— having its top and side walls curved longitudinally and transversely for shaping the shoulder or other portion of the garment thereto and permitting the 5 same to be pressed thereon if desired, the lower portion of said puff iron being normally disposed in a substantially horizontal plane and is provided with a central lengthwise conduit —15— having one end connected by a vertical passage —16— to the 10 interior of the chamber —14— and its other end connected to a steam distributing chamber —17— having a substantially flat perforated bottom wall —18— and an imperforate 15 top wall —19— between the chambers —17— and —14—.

The hub —12— in which the steam conduit —15— is formed is preferably made 20 separate from the main body of the puff iron and its upper portion is provided with an annular flange —20— adapted to fit in the corresponding recess in the lower side of the rear end of the main body of the puff iron as shown in Figure 3, the 25 two parts being secured together by screws —21— while the rear end of the chamber —17— extends downwardly across the adjacent end of the conduit —15— and is provided with an opening —15'— forming a 30 continuation of said conduit to connect the latter with the distributing chamber —17—.

The hub —12— is provided with a vertical guide opening —22— alined with the 35 vertical passage —16— for receiving a valve stem —23— having at its upper end a valve —24— which is normally seated in the upper end of the passage —16— to normally close communication between the chamber —14— and conduit —15— leading to the 40 distributing chamber —17—.

A coil spring —25— surrounds the lower end of the valve stem —23— between the lower wall of the conduit —15— and shoulder —9— to assist in closing the valve 45 —24— when the puff iron is in its normal horizontal position with the lower end of the front wall of the hub resting upon the flange —8— in which condition, the puff iron is held by the predominance of weight 50 of its front end in front of the pivot —11—.

A tubular pipe coil —26— has one end secured in the bracket —6— in alinement with a supply pipe —4— to form a continuation thereof and has its other end extended upwardly and secured in an opening —27— in the bottom wall of the chamber —14— for supplying steam thereto.

A similar pipe coil —28— has one end extended downwardly and secured in the 60 bracket —6— in alinement with a return pipe —5— and its other end extended upwardly and secured in an opening —29— in the bottom of the chamber —14— to permit the return of the steam and water 65 of condensation to the source of steam sup-

ply, the upper end of the coil —26— being extended into the chamber —14— some distance above that of the coil —28— and therefore, above the bottom of the chamber —17— to prevent the entrance of water of 70 condensation from said chamber into the steam supply pipe.

Suitable lugs —30— are cast upon the underside of the bottom —19— of the puff iron —1— to receive the intermediate portions of the perforated plate —18— and to permit the latter to be secured thereto by suitable screws —31— as shown by dotted lines in Figure 3.

A stop screw —32— is adjustable in a 80 threaded opening in the rear side of the hub —12— near the lower end thereof to cooperate with the adjacent portion of the upper end of the pedestal —2— for limiting the upward movement of the puff iron from 85 its normal position about the axis of the pivot —11— and thereby limiting the opening movement of the valve —24—.

It will be noted that the valve —24— and its stem —23— together with the abutment 90 —9— are located some distance to the rear of the axis of the pedestal —2— while the pivotal pin —11— is located some distance to the front of said axis and that the abutment —9— for said valve stem is in approximately the same horizontal plane 95 as the axis of the pivotal pin —11— so that when the front end of the puff iron is rocked upwardly from its normal position about the axis of the pivot —11—, the lower end of the valve stem will be forced 100 against the abutment —9—, thereby lifting the valve —24— from its seat and allowing the steam to pass from the chamber —14— through the passages —16—, —15— and —15'— into the distributing chamber 105 —17— and thence through the perforated plate —18— to a garment which may be held against the lower face of said plate.

The object in providing the coils —26— and —28— in the steam supply and return pipes is to render said pipes sufficiently 110 flexible to allow the desired vertical movement of the puff iron without straining any of the joints between said coils and bracket —6— and bottom wall of the puff iron.

Operation.

In steaming the shoulder or other part of the garment, the part to be steamed is placed in the hand and pressed against the under side of the perforated plate —18— with sufficient force to lift the front end of the plate against its own weight about the axis of the pivot —11— during which operation, the valve —24— will be opened by contact of the lower end of its stem —23— with the abutment —9— to allow the steam to pass 125 from the opening through the passages 130

—16,—15— and —15'— into the chamber —17— and thence through the perforated plate —18— on to the garment for softening and restoring the knap and rendering that 5 part of the garment more pliable for pressing upon the upper curved faces of the puff iron.

As soon as the pressure upon the under side of the perforated plate is relieved, the 10 puff iron will return to its normal position by its own weight, thereby permitting the valve —24— to close to cut off further communication between the heated chamber —14— and distributing chamber —17—, 15 this return movement being facilitated by the resiliency of the coils —16— and —28—.

By locating the abutments —8— and —9— at opposite sides of the pivot —11— the opening of the valve —24— under a 20 very slight lifting movement of the front end of the puff iron assures a close control of the supply of steam to the distributing chamber —17— and allows the valve to close when the puff iron is restored to its 25 normal position against the stop —8—.

What I claim is:

1. The combination of a support, a puff iron movably mounted upon the support and provided with a steam heated chamber and 30 a steam distributing chamber having a steam exit in one side and connected by a passage with the steam heated chamber, a steam conduit opening into the steam heated chamber, a normally closed valve in said 35 passage and means actuated by the movement of the puff iron from one position to another position for opening the valve.

2. In combination with a support, a puff iron hinged to the support to swing vertically and provided with a steam heated chamber and a steam distributing chamber having a steam exit on its under side and connected by a passage with the steam heated chamber, means for supplying steam 40 to said steam heated chamber, and means actuated by the movement of the puff iron from its normal position of rest for controlling the passage of steam from said steam heated chamber to the distributing 45 chamber.

3. In combination with a support, a puff iron hinged to the support to swing vertically and provided with a steam heated chamber and a steam distributing chamber, 50 a steam supply conduit leading to the heated chamber, an additional conduit connecting the heated chamber to the distributing chamber, a valve controlling the passage of steam through the second named conduit, 55 and means for opening the valve when the 60

puff iron is rocked from its normal position.

4. In combination with a support, a puff iron movable relatively to said support and provided with a steam heated chamber and a steam distributing chamber connected by a passage to the heated chamber and having a steam exit, a flexible pipe having one end secured to the support and its other end secured to the puff-iron for supplying steam 70 to the heated chamber, and means controlled by the movement of the puff-iron for opening and closing said passage.

5. In combination with a support, a puff iron pivotally mounted on the support to swing vertically and provided with a steam heated chamber and a steam distributing chamber, means for supplying steam to the heated chamber, a passage connecting the heated chamber with the distributing chamber, a valve controlling said passage and normally closed when the puff iron is in one position, and means for opening the valve when the puff iron is moved to a different 80 position.

6. A puff iron having a steam heated chamber and a steam distributing chamber provided with a steam exit in one side, steam supply and return pipes leading to and from the heated chamber, a steam 90 passage connecting the heated chamber to the distributing chamber, a valve controlling said passage, said puff iron being movable to different positions, and means for opening the valve when the puff iron is moved to one 95 of said positions.

7. The combination with a support, of a puff iron pivotally mounted upon the support to swing vertically and provided with a steam heated chamber and a steam distributing chamber having a steam exit in its lower side, a pipe coil having one end secured to the support and its other end secured to the puff iron and communicating with the heated chamber, means for supplying steam to the pipe coil, a stop at one side of the pivot for limiting the downward movement of the puff iron, an abutment at the opposite side of the pivot, and a valve controlling said passage and adapted to engage said abutment to open the valve when the puff iron is rocked from its normal position.

In witness whereof I have hereunto set my hand this 29th day of May 1922.

CHARLES E. SKELTON.
